Primary Examiner—Martie Thompson*Attorney, Agent, or Firm*—Cushman, Darby & Cushman IP Group of Pillsbury Madison & Sutro LLP[57] **CLAIM**

The ornamental design for a battery operated pencil sharpener, as shown and described.

DESCRIPTION

FIG. 1 is a perspective view of a battery operated pencil sharpener showing our new design, looking at the top, from the left side;

FIG. 2 is a left side elevational view thereof, the right side thereof being a mirror image thereof;

FIG. 3 is a top plan view thereof;

FIG. 4 is a bottom plan view thereof;

FIG. 5 is a front elevational view thereof; and,

FIG. 6 is a rear elevational view thereof.
